DISTANCE INDICATOR

Carl F. Davis, Jr., Knoxville, Tenn.

Application December 27, 1946, Serial No. 718,715

4 Claims. (Cl. 73—379)

1

This invention relates to a new and improved distance indicator and more specifically to an indicator calibrated to indicate the distance in yards a golf ball would travel.

The primary object of this invention resides in the provision of an arrangement whereby a golf ball is freely supported in a position adapting it to rotate in a circle when driven by a golf club and said rotation of the golf ball allowing the indication of the distance in yards which the golf ball would have travelled had it been free to travel in the course of its normal flight.

Another object of this invention is the provision of such an arrangement as set forth herein which provides for a small and compact unit which may be assembled in or out of doors to enable a person to practice golf in a convenient location and enable him to improve his swing and game by the adjusted calibrations produced on the instrument indicating the abilities which he is displaying during his practice.

Still another object of this invention is the provision of a device of the character described which has a minimum of simple and durable working parts and a device which in its entirety is of a simple, economical and practical use.

Still further objects, advantages and improvements in this invention will readily appear when the following description is read in the light of the accompanying drawings in which:

Fig. 1 is a side elevation of the assembled device.

Fig. 2 is a front elevation of the assembled device.

Fig. 3 is a vertical section taken on line 3—3 of Fig. 1.

Fig. 4 is a top elevation of Fig. 3 as indicated by line 4—4.

Referring now to the accompanying drawings which illustrate the preferred embodiment of this invention and in which like numerals indicate similar parts throughout A designates a flat horizontal base or supporting block to which is secured adjacent one face thereof a vertical U-shaped tube 1 which extends upwardly therefrom for a spaced distance and which carries thereon an adjustable set screw collar 2 adapting the vertical adjustment and support of a cylindrical rod 3 within the U of the tube 1.

The upper end of the cylindrical rod 3 terminates in a horizontal leg 4 on which is supported vertically a housing 5 in which there is mounted a horizontal cylindrical bearing 6 opening through said housing.

A rotatable pin 7 is mounted in the bearing

2

6 to extend therethrough on either side thereof, and an elongated arm 8 is vertically secured to the outer end of the pin to extend downwardly therefrom to a spaced distance above the base member A where it bends angularly outward away from the base for a spaced distance to a point slightly above the floor or ground beneath the base. A horizontal housing 9 is secured to the bottom end of the arm 8 in a horizontal plane transverse the alignment of the axis of the pin 7, and a threaded stud 10 is projected through the housing 9 carrying a golf ball 11 on one outer termination thereof. A coil spring 12 is secured around the stud 10 between the housing 9 and the golf ball 11 forming a resilient cushioning seat for said ball against said housing, and a wing nut 13 is secured on the second end of the housing about the stud 10 adjustably securing its extended position from the housing.

Thus it may be seen that by striking the ball 11 on the face thereof disposed oppositely from the housing 9 and the spring 12 the ball will be caused to rotate the arm 8 upon the pin 7 in a circle thereabout, for the number of rotations which the force and accuracy with which the ball is hit will cause. The upper extended opposite end of the arm 8 carries an adjustable counterweight 14 therein adapted to adjustably balance and properly position the depending motionless position of the golf ball 11.

The second extended end of the shaft 7 is fitted in a rectangular bracket 15 secured horizontally from the bearing 5 by braces 16 and said end carries a circular gear 17 thereon within the bracket 15. A pin 18 is rotatably mounted in the bracket 15 in a horizontal plane directly above the gear 17 and carries thereon an enlarged gear 19 adapted for rotatable engagement with the gear 17 of the shaft 7 and which carries a second smaller gear 20 thereon adapted for rotatable engagement with a second larger gear 21 which is also rotatably mounted within said bracket directly above the gear 20 on a pin 22 which extends horizontally through said bracket and which is rotatably mounted therein. This arrangement forms a calibrated geared reduction means for the predetermined calibration of the distance which said ball would travel in its normal flight.

A pulley 23 is secured to the extended end of the pin 22 directly beneath a second larger pulley 24 which is supported thereabove from a brace 25 carried above the original housing 5 and a cross brace 26 and support 27 therefor. This second pulley 24 carries a ratchet toothed ar-

arrangement 28 thereon which is adapted to be engaged by a spring arm 29 secured to the cross brace 26 adjacent said pulley.

A pin 30 on which said second pulley 24 is rotatably mounted extends through said cross brace 26 to an outwardly disposed position through the center of the face of a dial 31 secured to the front of the machine at the top of the brace or supporting arm 25, and said pin 30 carries an indicating arm 32 thereon adapted for rotation about the face of the dial 31.

A resilient rubber band 33 or the like interconnects the two pulleys 23 and 24, and adapts the rotation of the upper pulley 24 from the lower pulley 23 when said shaft 1 is rotated by the rotation of the ball 11 and arm 8 thereon through the medium of the reduction gears described, and said pulley 24 acting to rotate the indicating arm 32 about the face of the dial to indicate by the calibrated numerals on the face of the dial the yardage which the golf ball would have normally travelled in its free flight thus enabling the player using the device to know and recognize the faults and probable necessary improvements in his swing.

The indicator arm 32 is so arranged that it will slip on its shaft if turned in a counter-clockwise manner to enable the operator to bring said indicator to its zero position on the dial after each indication thereof, and the spring arm 29 and teeth 28 on the pulley 24 form a ratchet arrangement permitting the clockwise rotation of the pulley 24 enabling the actuation of the indicator, but forming a ratchet lock against counter-clockwise rotation of the pulley 24 thus locking the shaft 30 against rotation in a counter-clockwise movement allowing the slippage return of the indicator to zero.

Thus it may be seen that by striking the golf ball in a clockwise direction the ball will rotate on its supporting arm about the pin rotating the gears and pulleys described hence giving a predetermined calibration of the distance said ball would have travelled. It may also be seen that the force with which the ball is struck is not the only determining factor in the calibration as poor angular striking such as would normally cause a hook or slice will tend to give a two directional force to the ball and reduce its one directional rotation showing corresponding reduced calibration. This induces the person practicing to improve the most important factor in his swing which is his timing and reduce his tendency to "murder" the ball and forsake effort for timing.

Having thus described and explained the construction and operation of this invention and with full belief that modification in size, shape and general characteristics would not depart from the spirit of this invention what I desire to claim is:

1. A distance indicator of the character described comprising, a vertical standard, a vertical extension adjustably carried by said standard, a housing carried by said extension, a horizontal bearing carried by said housing, a shaft rotatably mounted in said bearing, an elongated arm secured vertically intermediate its length to the forward extension of said shaft, a counter-bal-

anced weight adjustably secured to the upper end of said arm, a golf ball carried by the normally depending end of said arm, a pulley wheel rotatably carried by said housing, double reduction gearing means interconnecting the rearward extension of said shaft and said pulley, a horizontal pin rotatably supported at an extended distance above said housing, a dial indicator carried by said pin, a second pulley wheel carried on a rearward extension of said indicator dial pin above said first pulley, driving means interconnecting said pulleys, and means adapting the said ball when struck to rotate said pin for the purpose described.

15 2. A device as set forth in claim 1 wherein, a horizontal housing is carried at the lower end of the elongated arm, an extension is carried slidably in alignment with and by said housing, a coil spring surrounding said extension, and a golf ball is carried by said extension seating against said spring and being normally held in an extended position from said housing thereby for the purpose described.

20 3. A device as set forth in claim 1 wherein, a ratchet wheel is carried by said upper pulley, a wheel engaging arm is carried adjacent said wheel, said ratchet means allows free rotation of said pulley in a clockwise direction only, and means adapting said dial indicator to rotate freely on said pin in a counter-clockwise direction for the purpose described.

25 4. A distance indicator of the character described comprising a vertical standard, a vertical extension carried by said standard, a housing carried by said extension, a horizontal shaft rotatably supported in said housing and having each of its ends projecting beyond the latter, an elongated arm secured vertically intermediate its length to one of the projecting ends of said shaft, 30 a counter-balanced weight on the upper end of said arm, a golf ball carried by the normally depending end of said arm, a pulley wheel arranged contiguous to and spaced from the other of the projecting ends of said shaft and rotatably carried by said housing, reduction gearing means 35 inter-connecting the other of the projecting ends of said shaft and said pulley wheel, a horizontal pin rotatably supported at an extended distance above said housing, a dial indicator carried by 40 said pin, a second pulley wheel on said pin, driving means inter-connecting said pulley wheels and means operatively connected to said ball adapting the ball when struck to cause rotation of said arm and shaft for the purpose described.
